UNITED STATES PATENT OFFICE.

HENRY F. BELCHER, OF CHICAGO, ILLINOIS, ASSIGNOR TO THE LUXFER PRISM PATENTS COMPANY, OF SAME PLACE.

PROCESS OF FORMING ORNAMENTAL PLATES.

SPECIFICATION forming part of Letters Patent No. 642,196, dated January 30, 1900.

Application filed April 21, 1898. Serial No. 678,436. (No specimens.)

To all whom it may concern:

Be it known that I, HENRY F. BELCHER, a citizen of the United States, residing at Chicago, in the county of Cook and State of Illinois, have invented a certain new and useful Improvement in Processes of Forming Ornamental Plates, of which the following is a specification.

My invention relates to ornamental plates for windows and the like and the process of forming the same.

My invention is illustrated in the accompanying drawings, wherein—

Figure 1 is a view of a plate made up of a series of tiles or the like. Fig. 2 is a view of the device shown in Fig. 1 after it has been subjected to my process. Fig. 3 is a section on line 3 3, Fig. 2. Fig. 4 shows a modified construction.

Like letters refer to like parts throughout the several figures.

In making up designs or the like of ornamental material—such, for example, as glass—it is often desirable to form the glass or other material with curved surfaces in accordance with some prearranged plan. It has heretofore been the practice to form special molds to mold the glass of the desired shape and then to unite the several pieces together in their proper relation. This operation is exceedingly difficult and expensive.

The object of my present invention is to provide an ornamental device of this description in a cheap and simple manner.

Referring now to the drawings, I have illustrated in Fig. 1 a series of tiles A united into a plate, the tiles being separated by the cross-pieces B and the plate being surrounded by a suitable frame C. This frame may be formed in any desired manner; but I prefer to frame the tiles by interposing metallic strips between them—such, for example, as strips of copper—and immersing the whole in an electrolytic bath, thus depositing metal on the cross-strips, which engages the tiles and binds them firmly together. If a plate of ornamental glass is desired, the pieces of glass are cut from plain glass of any description and are bound together in a suitable frame. The glass is then heated in any desired manner, and when it becomes sufficiently heat-

ed to make it plastic the several pieces are pressed outwardly until the desired shape and curvature are obtained. This result may be achieved in any desired manner. For example, I may place the entire plate in a furnace of any description and heat it to the desired temperature and then force the several pieces of glass outwardly by simply pressing upon them with any suitable instrument. The glass when so treated elongates or stretches and on becoming cool retains the shape into which it has been pressed. In Fig. 2 I have shown a view of the plate illustrated in Fig. 1 after it has been treated in this manner, a cross-section of the plate being shown in Fig. 3. In this view I have shown the cross-pieces B as projecting beyond the face of the plate, the plate being supported upon these cross-pieces while the glass is being pressed to its proper shape. It is of course evident that any suitable construction may be used. For example, instead of making the pieces B support the plate I may make them of ordinary thickness and provide a suitable frame, as shown in Fig. 4, upon which the plate is supported, the frame resting upon the cross-pieces B. This allows room for an outward movement of the tiles A, and any other construction whereby this result may be produced may be equally efficient. It will thus be seen that by this method I am enabled to produce a plate made up of a series of pieces of glass—for example, the glass having curved surfaces of any description—and that I am further enabled to make this plate at a very little cost.

I have illustrated in the drawings a simple construction in order to make my invention clear; but it is of course evident that this construction may be applied to the most complicated designs. I therefore do not wish to be limited in any manner to the construction shown.

I have shown a construction in which I have formed all the tiles or pieces A curved; but it is of course evident that some may be left straight and others curved and that any suitable form of tile may be obtained by this process.

I claim—

1. The process of forming ornamental plates

from a series of tiles, which consists in binding the tiles into a suitable plate, then heating the tiles and then bending such tiles to the desired shape.

5 2. The process of forming ornamental plates from tiles or the like, consisting in placing the tiles in proximity to each other with their edges slightly separated, then inserting metallic cross-pieces between the edges of the 10 tiles and providing the whole with a surrounding frame, then immersing the tiles and associated parts in an electrolytic bath and depositing metal upon the cross-pieces so as to bind the tiles together, then heating the tiles until 15 they become plastic, then forming the tiles into the desired shape.

3. As an article of manufacture, an orna-

mental plate consisting of a series of tiles bound together in a suitable frame, said tiles being stretched after they are placed in the 20 frame so as to be moved out of their original planes.

4. The process of forming ornamental windows, which consists in binding a series of tiles into a permanent frame with metallic 25 strips interposed between the tiles, then heating the tiles while in said permanent frame and then bending such tiles to the desired shape, substantially as described.

HENRY F. BELCHER.
